Specification for Design.

Patented Oct. 25, 1921.

Application filed March 22, 1921. Serial No. 454,486. Term of patent 14 years.

To all whom it may concern:

Be it known that I, WILLIAM J. GAGNON, a citizen of the United States of America, and residing at Bridgeport, in the county of Fairfield and State of Connecticut, have invented a new, original, and ornamental Design for a Tassel, of which the following is a specification, reference being had to the accompanying drawing, forming part thereof.

The drawing is an elevation of a tassel embodying my design.

I claim:

The ornamental design for a tassel, substantially as shown.

In testimony whereof I have signed my name to this specification.

WILLIAM J. GAGNON.
